ELECTROLYTIC CELL

Einar Sorensen, Rumford, Maine, assignor to Oxford Paper Company, a corporation of Maine

Application October 26, 1938, Serial No. 236,999

8 Claims. (Cl. 204—220)

This invention relates to electrolytic cells of the circulating mercury type for producing chlorine and sodium hydroxide from brine. Such a cell is disclosed in my prior patents, Nos. 5 2,104,677, 2,104,678 and 2,104,679, issued January 4, 1938.

The cell of the present application, in general construction and operation, is similar to the cell disclosed in my prior patents referred to but embodies certain improvements hereinafter described and claimed.

The cell disclosed in the above mentioned patents has a decomposing compartment and an oxidizing compartment. Mercury is circulated 15 in a tortuous path through the decomposing compartment and then over grooved graphite plates located in the oxidizing compartment. The mercury in the decomposing compartment constitutes the cathode of an electric circuit. 20 Graphite plates located above the mercury in the decomposing compartment constitute the anodes. Brine is admitted to the decomposing compartment and when an electric current passes between the graphite plates and the mercury, 25 chlorine is liberated from the brine and part of the mercury forms an amalgam with the sodium of the brine. The mixture of mercury and amalgam flows out of the decomposing compartment into the oxidizing compartment where it passes over the grooved graphite plates. Water is fed 30 into the oxidizing compartment and by the electrolytic action set up in this compartment the amalgam is decomposed and the sodium reacts with the water to form sodium hydroxide solution. 35 The mercury thus freed of its sodium then enters a pump chamber in which a rotary pump lifts the mercury and returns it to the decomposing compartment.

The principal object of the present invention is 40 to improve certain details of the oxidizing compartment of the cell shown in my prior patents.

In accordance with the present invention the grooved graphite plates over which the mixture 45 of mercury and amalgam flows in the oxidizing compartment are positioned and supported in a pan preferably made of black iron although it may be made of, or have a surfacing of, nickel or other material which is sufficiently resistant to the caustic. The pan is removably mounted 50 in the oxidizing compartment and the graphite plates are removably clamped in the pan.

It is advantageous to maintain a relatively 55 deep layer of mercury and amalgam flowing through the grooves in the graphite plates in the oxidizing compartments as I have found

that by so doing a more thorough decomposing of the amalgam can be obtained. My theory, which explains this result but to which I do not wish to be limited, is that the amalgam exists in the mercury as a mechanical mixture and since it is of lower specific gravity it will rise to the top if given the opportunity. Therefore, when a deep layer of mercury and amalgam is employed the amalgam is given a chance to rise to the top of the mercury and thus come into 10 contact with the caustic solution and be denuded. Moreover, the greater depth of mercury and amalgam in the grooves provides more contact between the mercury-amalgam mixture and the graphite which is thought to contribute to 15 the denuding action. In order to regulate the depth of the mercury-amalgam mixture flowing over the graphite plates and to insure the presence of a relatively deep layer of it, I provide a mercury seal through which the mercury passes 20 in leaving the metallic pan, and I provide the mercury seal with an adjustable over-flow outlet whereby the depth of the mercury flowing through the grooves in the graphite plates can be regulated.

The pan above referred to is so supported in the oxidizing compartment that there is a space under it. During operation of the cell the sodium hydroxide solution surrounds the pan and therefore some of it occupies the space under the pan. 30 This space affords a convenient and practical location for a heating instrumentality, so I provide a steam pipe, or the like, at this place which may be used to heat the sodium hydroxide solution when this is found desirable.

The improved cell is shown in the accompanying drawings in which:

Figure 1 is a plan view of the cell with the cover and anode assembly of the decomposing compartment removed;

Fig. 2 is a longitudinal section through the oxidizing compartment taken on the line 2—2 of Fig. 1;

Fig. 3 is a transverse section through the oxidizing compartment taken on the line 3—3 of Fig. 1;

Fig. 4 is a longitudinal section through the decomposing compartment taken on the line 4—4 of Fig. 1;

Fig. 5 is a transverse section, through both 50 compartments taken on the line 5—5 of Fig. 1; and

Fig. 6 is a transverse section through both compartments taken on the line 6—6 of Fig. 1.

The improved cell has an external casing 1, 55

preferably made of steel, which is generally rectangular in shape as shown in Fig. 1. It is divided into two compartments by a longitudinal partition 2. One of these compartments designated 3 is the decomposing compartment, and the other one designated 4 is the oxidizing compartment. As shown at 5 in Figs. 5 and 6 that part of the casing which houses the oxidizing compartment projects downwardly to a lower level than the part of the casing which houses the decomposing compartment.

Brine to be treated enters the decomposing compartment through an inlet 6 (Figs. 1 and 4). The mercury enters the decomposing compartment from the oxidizing compartment at 7. Upon reaching the decomposing compartment it first flows through a transverse passage 8 and then longitudinally in a tortuous path successively through channels 9, 10 and 11, as indicated by the arrows in Fig. 1. The right-hand end of the channel 11 communicates with a passage 12 through which the mercury leaves the decomposing compartment and enters the oxidizing compartment. The various passages and channels in the decomposing compartment may be molded in concrete 13.

The mercury flowing in a thin layer through the decomposing compartment forms the cathode of an electric circuit. It makes electrical contact 30 through vertical openings 15 in the concrete with metal strips 14 (Figs. 1 and 4) embedded in the concrete. The metal strips 14 are electrically connected to a bus bar 16 (Fig. 4).

A cover 17 for the decomposing compartment (Fig. 4) supports a number of graphite plates 18 which constitute the anode of the electric circuit. The lower faces of the plates 18 lie just above the surface of the mercury flowing through the channels 9, 10 and 11. The graphite plates 18 are connected in the electric circuit by conductors not shown in the drawings. When current passes through the brine between the graphite plates and the mercury, chlorine is liberated from the brine and part of the mercury forms an amalgam 45 with the sodium of the brine. The spent brine together with the liberated chlorine is discharged from the decomposing compartment through an outlet 19. The mixture of mercury and amalgam flows through the passage 12, hereinbefore described, into the oxidizing compartment. The decomposing compartment, in construction and operation, is practically identical with the decomposing compartment of the cell shown in my prior patents above referred to and requires no 55 further description.

The mixture of mercury and amalgam entering the oxidizing compartment through the passage 12 first flows into a well 20 (Figs. 1 and 5) formed in a body of concrete at the right-hand end of 60 the oxidizing compartment. It then passes through a conduit 21 (Figs. 1 and 2) and up through an elbow 22 and is discharged into the pan 24 hereinbefore referred to. The elbow enters the bottom of the pan and is fastened to the 65 pan by a lock nut 22'. The lower portion of the well 20, the conduit 21, and the elbow 22, form a mercury seal which prevents brine from passing along with the mercury into the oxidizing compartment. When the mercury reaches the pan 70 24 it flows over grooved graphite plates, shown at 23, positioned in and supported by the pan.

The pan 24 is preferably black iron but it may be made of, or surfaced with, any material which is resistant to the action of the caustic soda solution formed in the oxidizing compartment. The

pan is supported in the oxidizing compartment at an elevated position to bring the graphite plates to the proper level and to provide a space below the pan for the purposes hereinafter mentioned. It may be supported on angle irons 25 (Figs. 1 and 2) which span the oxidizing compartment, and are welded at their ends to the side walls of the casing 1. In the present instance three of these angle irons are shown. The pan may be removably supported by these angle irons 10 by simply resting on them but preferably it is removably clamped to them. Passing transversely over the top of the pan immediately above the angle irons 25 are three angle irons 26 whose extremities are connected to the angle irons 25 by 15 bolts 27. Under each angle iron 26 there is a clamping element 28, made of any suitable caustic resistant material, which bears on the graphite plates. Tightening of the bolts draws the angle irons 26 toward the angle irons 25 and firmly retains 20 the graphite plates in the metallic pan and firmly retains the pan on the angle irons 25.

Additional retaining means for the graphite plates may be provided if so desired by passing transversely under the pan a number of T-irons 29 25 (Figs. 2 and 3) to the ends of which are welded bolts 27'. An angle iron 26' extends transversely over the pan above each T-iron and is connected at its extremities to the bolts 27'. A clamping element 28' is located under each angle 30 iron 26' so that when the angle irons 26' are drawn toward the T-irons 29 by tightening the bolts the graphite plates will be clamped in the pan by the clamping elements 28'.

Inasmuch as the bottom of the graphite plates 35 is uneven, the plates are preferably positioned on a layer of caustic resistant cement, or similar material, indicated at 23' in Fig. 3. This material levels the unevenness at the bottom of the plates and equalizes the stress applied by the clamps. 40 It also fills up any pockets under the plates which might lodge mercury or caustic solution that happened to seep through the plates. This material is also used to fill in the crevices between and around the edges of the plates to prevent 45 mercury or caustic solution from finding their way under the plates.

The graphite plates may be readily and quickly removed by removing the nuts on the bolts 27 and 27' and then removing the angle irons 26 and 26' 50 and the clamping elements 28 and 28'. This also permits removal of the pan when the lock nut 22' on the elbow 22 is removed and when the herein-after described mercury discharge pipe is disconnected. By removing only the nuts on the bolts 55 27, the pan, with the graphite plates still clamped in it by the bolts 27', may first be removed as a unit if so desired, and the graphite plates later removed from the pan.

After the mercury flows through the grooves of 60 the graphite plates 23 it is discharged from the pan 24 by a pipe 30 (Figs. 1 and 6). This pipe is generally U-shaped and forms a mercury seal which prevents the caustic solution formed in the oxidizing compartment from being discharged 65 with the mercury. The pipe 30 has an adjustable overflow outlet which preferably comprises a threaded nipple 31 (Fig. 6). By turning this nipple it can be vertically adjusted whereby the level of the mercury flowing over the graphite 70 plates 23 can be regulated to maintain in the oxidizing compartment the desired relatively deep layer of mercury. As the mercury leaves the nipple 31 it flows directly into a pump well 32 molded in a body of concrete at the left-hand end of the 75

oxidizing compartment. A rotary pump 33 picks up the mercury and discharges it into a transverse trough 34 in the manner described in my prior patents. It is discharged by the trough into a generally U-shaped pipe 35 by means of which it is conducted back to the decomposing compartment. The pipe 35 constitutes a mercury seal which allows only mercury to pass into the decomposing compartment.

10 The water that is required in the oxidizing compartment is admitted from a pipe 36 into the pump well 32. It is picked up by the rotary pump and is discharged together with the mercury into the trough 34. The water, of course, floats on top 15 of the mercury in the trough 34 and it is discharged through a pipe 37 directly into the oxidizing compartment.

In the oxidizing compartment the amalgam is decomposed and the sodium reacts with the 20 water to form sodium hydroxide solution. The sodium hydroxide solution thus formed fills the oxidizing compartment and completely surrounds the pan 24. It flows from the oxidizing compartment through a pipe 40 into the hydrometer compartment 41 of a casing 42 (Fig. 1) from which it flows over the upper edge of a partition 43 into a second compartment 44 and is discharged through a pipe 45 communicating with the bottom of this compartment. The caustic 25 soda solution is maintained at the proper level in the oxidizing compartment by adjusting the level of the upper edge of the partition 43. The space under the metallic pan 24 may accommodate the instrumentality used for heating the 30 caustic solution. In the present instance this is shown as a steam pipe 39 (Figs. 1 and 3).

Preferably the caustic solution nowhere comes in contact with any concrete. The bodies of concrete at the ends of the oxidizing compartment may be faced with black iron sheets 38 (Fig. 2) to prevent contact of the caustic solution with them.

Some of the advantages resulting from the improvements herein described are as follows: 45 The cost of the cell is reduced due to the simplicity of installing the black iron pan and the graphite plates. The maintenance cost is reduced as the graphite plates in the black iron pan may be readily removed, repaired or replaced. The 50 pan may be removed without much difficulty when repairs are necessary. Fewer graphite plates than usual may be used and this makes for economy.

Supporting the pan at an elevated position in 55 the oxidizing compartment provides a space under it in which any foreign impurities that might enter with the water can settle out. This space affords a convenient location for the heating pipe where it is immersed in the liquid body of caustic 60 thus insuring uniform distribution of the heat. Moreover, the space under the pan increases the amount of caustic solution in the oxidizing compartment thus providing it with a certain amount of thermal inertia by making it less susceptible 65 to temperature changes.

The improved cell is capable of producing uncontaminated caustic solution of high concentration. Three of the improvements herein described, i. e., the adjustable overflow outlet for 70 the mercury leaving the oxidizing compartment; the heating pipe; and the pan for supporting the graphite plates in the oxidizing compartment all contribute toward this result as follows:

The adjustable overflow outlet for the mercury 75 seal enables the desired relatively deep layer of

mercury to be maintained in the oxidizing compartment thus facilitating denuding of the amalgam and thereby making it possible to obtain a high strength caustic solution.

The heating pipe plays its part in making it 5 possible to produce caustic solution of high concentration, in two ways, first, by maintaining a temperature in the oxidizing compartment at which the denuding of the amalgam is most effectively accomplished, and second, by preventing crystallization of the high strength caustic after it is produced. When caustic solution of high strength is being produced the caustic will crystallize out and deposit unless the solution is heated to approximately 95° C. By the use of 10 15 the heating pipe the caustic solution may be maintained at the proper temperature to prevent such crystallization.

The pan eliminates danger of contamination 20 of the strong caustic solution. If strong caustic solution is allowed to come in contact with concrete it will dissolve portions of the concrete thereby contaminating the caustic solution. The pan eliminates the necessity of setting the graphite plates in concrete as heretofore and 25 therefore contamination of the caustic solution by dissolved portions of concrete is avoided.

I claim:

1. In an electrolytic cell of the circulating mercury type for producing chlorine and sodium 30 hydroxide from brine the combination of an oxidizing compartment, a pan in said compartment, graphite in said compartment, said pan extending in a general horizontal direction and serving as a container for mercury and for said 35 graphite, an inlet for conducting mercury to one part of said pan, an outlet for discharging mercury from another part of the pan whereby substantially the entire flow of the mercury is horizontally over the graphite in the pan from said 40 inlet to said outlet, means for supporting said pan in spaced relation with the bottom of the oxidizing compartment whereby the caustic soda solution formed in the oxidizing compartment will occupy the space above and below said pan, 45 the mercury being discharged from said pan and said compartment without passing into the space below the pan.

2. In an electrolytic cell of the circulating mercury type for producing chlorine and sodium 50 hydroxide from the brine the combination of an oxidizing compartment, a plurality of graphite plates in said compartment, a metallic pan in said compartment, said pan extending in a general horizontal direction and serving as the container for mercury and for said graphite plates, 55 means for removably clamping the graphite plates in said pan, an inlet for conducting mercury to one part of said pan, an outlet for discharging mercury from another part of the pan 60 whereby substantially the entire flow of the mercury is horizontally over the graphite plates in the pan from said inlet to said outlet, means for removably supporting said pan in spaced relation with the bottom of the oxidizing compartment 65 whereby the caustic soda solution formed in the oxidizing compartment will occupy the space above and below said pan, the mercury being discharged from said pan and said compartment without passing into the space below 70 the pan.

3. Apparatus in accordance with claim 1 in which means for heating the caustic soda solution is located in the space below the metallic pan.

4. In an electrolytic cell of the circulating mercury type the combination of an oxidizing compartment, a plurality of graphite plates in said compartment, a pan in said compartment, said pan extending in a general horizontal direction and serving as a container for mercury and for said graphite plates, an inlet for conducting mercury to one part of said pan, an outlet for discharging mercury from another part of the pan 10 whereby substantially the entire flow of the mercury is horizontally over the graphite plates in the pan from said inlet to said outlet, means for supporting said pan in spaced relation with the bottom of the oxidizing compartment, at least one member extending transversely under the pan, at least one member extending transversely over the pan, means to draw said members toward each other, and a clamping element disposed between the upper member and the graphite plates whereby the graphite plates will be clamped in the pan when said members are drawn toward each other, the mercury being discharged from said pan and said compartment without passing into the space below the pan. 20
5. In an electrolytic cell of the circulating mercury type the combination of an oxidizing compartment, a plurality of graphite plates in said compartment, a pan in said compartment, said pan extending in a general horizontal direction and serving as a container for mercury and for said graphite plates, an inlet for conducting mercury to one part of said pan, an outlet for discharging mercury from another part of the pan whereby substantially the entire flow of the mercury is horizontally over the graphite plates in the pan from said inlet to said outlet, at least one member extending transversely under the pan, at least one member extending transversely over the pan, means connected to said members 30 to draw the upper member toward the lower member, and means whereby the drawing of the upper member toward the lower member clamps the graphite plates in said pan, the mercury being discharged from said pan and said compartment without passing into the space below the pan. 40
6. In an electrolytic cell of the circulating mercury type the combination of an oxidizing compartment, graphite in said compartment, said pan extending in a general horizontal direction and serving as a container for mercury and for said graphite, an inlet for conducting mercury to one part of the pan, an outlet for discharging mercury from another part of the pan whereby substantially the entire flow of the mercury is 45
- horizontally over the graphite in the pan from said inlet to said outlet, a plurality of members spanning the oxidizing compartment and extending transversely under the pan and on which said pan is supported, and a plurality of members extending transversely over said pan and cooperating with the first mentioned members to clamp the pan thereto, the mercury being discharged from said pan and said compartment without passing into the space below the pan. 50
7. In an electrolytic cell of the circulating mercury type for producing chlorine and sodium hydroxide from brine, the combination of an oxidizing compartment, graphite in the oxidizing compartment, a receptacle extending in a general horizontal direction in said compartment and serving as a container for said graphite and for mercury, the surface of said receptacle being substantially unaffected by sodium hydroxide solution, an inlet for conducting mercury to one part of said receptacle, a mercury seal through which the mercury is discharged from another part of the receptacle whereby substantially the entire flow of the mercury is horizontally over the graphite in the receptacle from said inlet to 55 said mercury seal, said mercury seal having a vertically adjustable overflow outlet whereby the mercury in the receptacle may be maintained at a predetermined level and in a relatively deep layer, and means in the oxidizing compartment for heating the sodium hydroxide solution therein, the mercury being discharged from said receptacle and said compartment without passing into the space below said receptacle. 60
8. In an electrolytic cell of the circulating mercury type for producing chlorine and sodium hydroxide from brine the combination of an oxidizing compartment, a pan in said compartment, graphite in said compartment, said pan extending in a general horizontal direction and serving as a container for mercury and for said graphite, an inlet for conducting mercury to one part of said pan, a mercury seal through which mercury is discharged from another part of the pan whereby substantially the entire flow of the mercury is horizontally over the graphite in the pan from said inlet to said outlet, means for supporting said pan in spaced relation with the bottom of the oxidizing compartment, whereby the caustic soda solution formed in the oxidizing compartment will occupy the space above and below said pan, the mercury being discharged from said pan and said compartment without passing into the space below the pan. 65

EINAR SORENSEN. 55

CERTIFICATE OF CORRECTION.

Patent No. 2,226,784.

December 31, 1940.

EINAR SORENSEN.

It is hereby certified that error appears in the printed specification of the above numbered patent requiring correction as follows: Page 1, first column, line 55, for the word "compartments" read --compartment--; page 4, first column, line 49, claim 6, after "compartment," insert --a pan in said compartment,--; and that the said Letters Patent should be read with this correction therein that the same may conform to the record of the case in the Patent Office.

Signed and sealed this 4th day of February, A. D. 1941.

(Seal)

Henry Van Arsdale,
Acting Commissioner of Patents.
